EXPANSIBLE PISTON

Clarence S. Johnston, Amarillo, Tex.

Application November 10, 1933, Serial No. 697,485

4 Claims. (CL 309—12)

This invention relates to expansible pistons and has for its object the production of a simple and efficient means for facilitating the expansion of the piston and preventing the shrinking of the piston after it has once been expanded. 5

A further object of the invention is the production of a simple and efficient means for expanding a piston consisting of a plurality of diverging wedge-shaped pins which are so mounted as to facilitate the spreading or expansion of the piston skirt as the wedge-shaped pins are adjusted longitudinally. 10

A still further object of this invention is the production of a simple and efficient piston structure which is so assembled as to provide means for preventing the cracking or splitting of the piston while it is being expanded. 15

This application is an improvement on my prior Patent #1,890,511. 20

Other objects and advantages of the present invention will appear throughout the following specification and claims. 25

In the drawing:—

Figure 1 is a side elevation of the piston; 25
Figure 2 is a section taken on line 2—2 of Figure 1;

Figure 3 is a section taken on line 3—3 of Figure 2; 30

Figure 4 is a fragmentary bottom plan view of a portion of the inner end of the piston; 35

Figure 5 is a vertical sectional view taken on line 5—5 of Figure 2; 40

Figure 6 is a side elevation of a portion of the piston showing means for facilitating the withdrawal of the expansion wedge pins; 45

Figure 7 is a perspective view of one of the reinforcing or hinge plates adapted to be embedded or molded within the piston casting; 50

and 55

Figure 8 is a modified form of the invention showing one of the diverging pins and sockets threaded to provide a proper adjustment. 60

By referring to the drawing, it will be seen that Figure 10 designates the piston which is provided with a skirt 11, the skirt 11 being longitudinally split, as at 12, and having a split longitudinally extending boss 13 formed upon the inner face of the skirt, as shown clearly in Figure 2. This 65

longitudinal split boss 13 is provided with a wedge-shaped socket 14 extending longitudinally thereof, with which socket the split portion of the boss and skirt communicate. A threaded pin 15, also wedge-shaped, is threaded within the internally threaded socket 14 and a suitable wrench-receiving 70

knob 16 is formed upon the lower end of the pin 15 to facilitate the rotation of the pin 15 within the socket 14. As the pin 15 is rotated in a clockwise direction, it will be forced upwardly toward the outer end of the piston, thereby causing the skirt to be spread. 75

The piston skirt 11 is braced by means of the transversely extending web portions 17 which are preferably cast integrally with the skirt 11, and the piston skirt, as well as these web portions 17, is preferably formed of cast aluminum alloy as is common to the trade. These transversely extending web portions are provided with longitudinally extending expansion channels 18 which 80

channels taper toward the upper end of the piston, and the channels are also diverged outwardly away from the central longitudinal axis of the piston, as shown in Figures 1 and 3. These expansion channels 18 are preferably circular in cross-section, and are provided upon diametrical- 85

ly opposite sides, running transversely of the web portions 17, with relatively narrow expansion channels 19. In order to prevent the cast aluminum alloy web portions 11 from splitting or breaking under expansion and contraction, I 90

cast longitudinally extending steel hinge plates 20 within the web portions 17, as shown in Figure 2, and these hinge plates comprise substantially elongated steel reinforcing members having bent longitudinally extending edge flanges 21 and a 95

rolled longitudinally extending centrally located bead portion 22, the bead portion 22 of each hinge 20 being located in one of the diametrically opposite expansion channels 19 and extending out- 100

wardly and beyond the cast web portion 11. To anchor the plates 20 firmly in position, a plurality of apertures 23 are formed therein to permit the cast aluminum alloy to extend through the apertures and form a firm anchoring means. 105

These longitudinally extending rolled or bead portions 22 will permit of a proper expansion and contraction throughout substantially the entire length of the web portions 17 under the expansion and contraction of these web portions. The usual piston bosses 24 are carried by the oppositely arranged web portions 17, as shown in the drawing. 110

The tapering expansion channels 18 are adapted to receive the tapering pins 25 which pins are adapted to be driven into the expansion channels 18 for the purpose of spreading the skirt 11. The skirt 11 is split, as at 26, upon diametrically opposite sides and in substantial alignment with the central axis of the bosses 24, the split portions 26 preferably extending at an angle to the 115

longitudinal axis of the piston, as shown in Figure 1. The expansion pins 25 may be provided with knobs 27 at their lower ends for facilitating the operation of the pins, and in order to hold these pins 25 against accidental displacement, a flat locking spring 28 is employed for each set of pins upon opposite sides of the piston. These springs 28 are anchored within a boss 29 mounted upon each side of the piston below the piston bosses 24. This structure is shown in Figures 4 and 5. The ends of the spring 28 are preferably enlarged as indicated at 30, and suitable apertures 31 are formed in these enlarged portions 30 to fit over the knobs 27 of the pins 25 to hold the pins in position.

The lower ends of the tapering expansion pins 25 may be threaded, as at 32, for receiving a nut 33 which may be used to abut against the lower edge of the web portions 17 to facilitate the drawing of the piston pins 25 outwardly for adjustment or removal of the pins.

As shown in Figure 8, the expansion channel 18a may be internally threaded for receiving the externally threaded expansion pin 25a and this expansion pin 25a may be provided with hexagonal, square, or other wrench-receiving knob 27a and a suitable locking spring 28a suitably apertured may be employed for fitting over the knob 26a to hold the pin 25a in position. This pin 25a is similar to the pin 25 previously described with the exception of the threading of the pin and channel.

Having described the invention, what is claimed as new is:—

1. In combination with a piston having a split skirt, an integral web formed upon the inner walls

of the skirt, said web having an expansion channel, and a hinge member formed within the web and spanning said channel for reinforcing the same against splitting.

2. In combination with a piston having a split skirt, an integral web formed upon the inner walls of the skirt, said web having an expansion channel, and a steel hinge molded longitudinally within said web and spanning said channel for reinforcing the web and preventing the splitting thereof when the skirt is expanded.

3. In combination with a piston having a split skirt, a web formed integrally with the skirt and spanning the skirt, said web having a longitudinally extending expansion channel, a reinforcing member comprising a relatively flat plate cast within said web portion and provided with a laterally extending longitudinally formed rolled bead extending outwardly of the web and spanning said channel to provide a hinge, and expansion means adjustably mounted within the expansion channel.

4. In combination with a piston having a split skirt, a web formed integrally with the skirt and spanning the skirt, said web having a longitudinally extending expansion channel, a reinforcing member comprising a relatively flat plate cast within said web portion and provided with a laterally extending longitudinally formed rolled bead extending outwardly of the web and spanning said channel to provide a hinge, expansion means adjustably mounted within the expansion channel, and the hinge having turned edges to facilitate the anchoring of the hinge in said casting.

CLARENCE S. JOHNSTON.
